SPRAYING DEVICE FOR HEAT FUSIBLE MATERIAL

Manuel A. Sandora, San Francisco, Calif.

Application August 11, 1947, Serial No. 767,921

2 Claims. (Cl. 299—28.7)

1

This invention relates to a spraying device, and particularly to a device for spraying metal, glass, zinc, copper, brass, lead, plastics and the like in pulverized or dust form for the coating of metal and like surfaces.

An object of the invention is to provide a device for spraying a dust of the character mentioned in the presence of heat in such a manner that the heated dust particles are uniformly distributed over a surface to be coated and are fused upon the said surface at a substantially uniform thickness, and in which device the clogging of the device is obviated, and sensitive control is provided for the desired operations.

Another object of the invention is to provide a spraying gun or nozzle which is adjustable to various angles and which can be easily controlled in the various adjusted positions so as to feed the proper amount of dust to a nozzle heated by proper flames for the coating operation.

Another object of the invention is to provide a device for spraying and coating, of the character described, in which a constant feed of the material in pulverized or dust form is assured without clogging, and with adjustable control both as to the flow of the dust or pulverized particles as well as to the mixture of the heating medium at the nozzle.

A further object of the invention is to provide a spraying device of the character described, in which the fuel and oxygen or air feed is readily adjustable and is easily controlled by the operator, and in which the direction of the nozzle operation is readily adjustable to suitable angles, and in which the feeding of the pulverized coating medium to be blown through the nozzle is so regulated as to prevent clogging and failure of the device.

The essential features of the invention involved in the carrying out of the objects indicated are susceptible to modification, but preferred embodiment of the invention is shown in the accompanying drawings, in which:

Fig. 1 is a side view of the device partly in section showing the agitator as well as the spraying nozzle or gun;

Fig. 2 is an end view of the gun and nozzle portion of the device;

Fig. 3 is a sectional view of the device, the section being taken on the lines 3—3 of Fig. 2;

Fig. 4 is a sectional view of the control valves in the device, the section being taken on the lines 4—4 of Fig. 3;

2

Fig. 5 is a sectional view of the nozzle and gun device of my invention;

Fig. 6 is a sectional view of the portion of the nozzle where the fuel and gas are mixed and drawn in as well as portion of the dust or powder conduit, the section being taken on the lines 6—6 of Fig. 5;

Fig. 7 is a sectional view of the controlling device for the feeding of the powder or dust to the nozzle, the section being taken on lines 7—7 of Fig. 5;

Fig. 8 is another sectional view of the nozzle portion of the device, the section being taken on the lines 8—8 of Fig. 6;

Fig. 9 is a partly sectional side view of the device with a modified form of nozzle tip;

Fig. 10 is a sectional view of said modified form, the section being taken on the lines 10—10 of Fig. 9;

Fig. 11 is a sectional view of the modified form of the nozzle near the tip thereof, the section being taken on lines 11—11 of Fig. 9;

Fig. 12 is a cross sectional view of the modified form of the nozzle structure;

Fig. 13 is a partly sectional view of the agitator and pressure device for mixing and keeping the powdered particles and for blowing them into the conduit to the nozzle;

Fig. 14 is a perspective detail view of the air intake portion of said agitator; and

Fig. 15 is an end view at the air intake end of said agitator.

In its general organization, my invention includes a spray nozzle generally denoted by the reference numeral 1, a handle 2, adjustable connection 3 between the nozzle and the handle, a valve control device 4 for the conducting of the oxygen or air and gas to a nozzle, a dust flow control 6 to control the continuous flow of solid particles through the nozzle and an agitator and pressure feed device for the dust 7 for supplying the dust under pressure to the nozzle. While reference is made herein to dust to be blown through the nozzle for coating operation, it is to be understood that the word "dust" as herein used includes the various types of comminuted or pulverized particles which are fusible under the heat for the coating operation, which dust may be, according to the purposes of the coating, glass, zinc, copper, brass, lead or other metal, or plastics of various types.

The nozzle 1 includes a body 8 which has a passage 9 therethrough. An end of the passage 9 is enlarged for locating a dust conduit 11 therein. In the present illustration the enlarged end

50

12 of the passage 9 is tapered outwardly toward the outlet end 13 of the body 8. Through this passage 9 is extended the tube 11 of smaller diameter than the diameter of the passage 9. Upon said tube is an externally threaded portion 14 aligned with the outlet end 13 of the body 8, next to which are provided a pair of collars 16 and 17 spaced inwardly of the enlarged end 12, which collars are so tapered at the outer peripheries thereof as to fit into said tapering enlarged portion 12 of the passage 9 and to tightly engage said enlarged portion 12 in a predetermined position so that a gas intake 18 on said body 8 is positioned between the collars 16 and 17, and an air or oxygen intake 19 on said body 8 is positioned between the inner collar 17 and the intake end of the tube 9. The intake end of the conduit 11 is extended beyond the intake end of the nozzle body 8 and to the outside thereof, is suitably packed and it is exteriorly threaded as shown at 21. On this threaded end 21 is provided a lock washer 22 and nut 23 which bear against the intake end of the nozzle body 8 for tightly drawing the collars 16 and 17 into the enlarged end 12 of the passage 9 and to hold the conduit 11 in place.

Onto the externally threaded portion 14 of the conduit 11 is threaded a nozzle tip 24. The nozzle tip surrounds an outlet end 26 on the outlet stem 27 extended from the threaded portion 14 of the conduit 11. Said stem 27 is smaller than the inner diameter of the nozzle tip 24, so as to allow the passage of the combustible mixture through the space around said stem 27. The outlet end 26 is knurled substantially axially so as to emit spaced jets of combustible mixture around the entire outer periphery of said outlet end 26 of the conduit at the nozzle tip. The inner end of the nozzle tip 24 is enlarged into an internally threaded head 28 which fits into the outlet end 13 of the nozzle body 8 and is threadedly engaged with the threaded portion 14 on said conduit 11. It is to be noted that an intake chest 29 is formed between the collars 16 and 17 spaced from the surrounding periphery of the enlarged portion 12 of the passage 9 in the nozzle body 8. This intake chest 29 has radial intake holes 31 circumferentially spaced around the same, which extend from the outer periphery of said intake chest 29 into circumferentially spaced substantially axial holes 32, which latter in turn extend through the collar 17, the chest 29, the collar 16 and the threaded portion 14 so as to conduct air from the outside face of the collar 17 to the space inside of the head of the nozzle tip 24. The passage of the air or oxygen under pressure through the axial holes 32 draws in fuel from the space around the chest 29 and carries the same in the proper mixture to the space between the nozzle tip 24 and the stem 27 and out through the passages formed by the knurls or corrugations at the knurled outlet end 26. When this mixture is ignited at the discharge end of the nozzle tip 24 it forms a flame under pressure surrounding the outlet end of the passage of the conduit 11.

The conduit 11 has a passage 33 therethrough, which passage tapers outwardly from about the portion corresponding to the location of the collar 17 toward the tip or end of the knurled end 26 as particularly shown in Fig. 6 so that by its expanding action facilitates the flow of the dust particles toward the outlet end 26. As the coating particles in the form of fine dust are blown through the passage 33 of the conduit 11 and as they leave at the knurled end 26, they are heated

by the flames surrounding the knurled end 26 to a suitable temperature and are so regulated both in heat and consistency that they fuse and adhere evenly and uniformly upon the surface to be coated.

The handle 2 is a tubular handle through which are extended flexible tubes 34 and 36, to conduct gas and air or oxygen respectively to the intakes 18 and 19, to which intakes they are suitably secured.

The adjustable connection between the nozzle 1 and the handle 2 in the present form is accomplished by a pair of parallel links 37 one on each side of the nozzle body 8. These links are preferably curved at their upper end 38 and are pivotally held on suitable shafts 39, and are releasably clamped onto said shafts 39 and said body 8 by knurled nuts 41 as shown in Figs. 1 and 2. The lower ends of the respective links 38 are similarly pivoted on threaded shafts 42 extended from the opposite sides of the top of the handle 2 and are clamped in position by knurled nuts 43 as shown in said Figs. 1 and 2. Thus, the angle of the nozzle relatively to the handle 2 can be adjusted by loosening the knurled nuts 41 and 43 and turning the nozzle body 8 to the desired angle relatively to said handle 2 and then fastening the links 38 in said adjusted position. The operator can hold the handle 2 in the convenient usual position, yet the nozzle 1 is directed at the desired angle to the surface to be coated.

The control for the gas and oxygen or air includes a valve body 44 fixed in the lower end of the handle 2. The valves in the valve body 44 are arranged and controlled so as to permit the adjustment of the mixture by the control of the intake of the proper amount of gas and oxygen into the respective tubes 34 and 36. Each of the valve structures in said valve body 44 includes a valve seat 46 which leads into a valve chamber 47 substantially parallel with a radius of the valve body 44. From the valve chamber 47 extends axially to the top of the valve body 44 a valve outlet passage 48. The respective tubes 34 and 36 are secured and connected to the upper ends of the respective valve passages 48. It is to be noted that the valve seats 46 and their chamber 47 and outlet passages 48 are parallel and are spaced from one another so that the valves 49 seating on the respective valve seats 46 extend substantially parallel with the same radius to the same side of the body 44. Valve stems 51 extend from the respective valves 49, each through a bore 52. The bores 52 guide the respective valves 49 in their opening and closing movement. The outer end 53 of each bore 52 is threaded so as to receive therein a packing gland or nut 54, which packing gland or nut 54 has a recess 56 therein to accommodate a coil spring 57 which surrounds the stem 51 and bears at one end against the bottom of the recess 56 and the other end against the valve 49 to normally urge the valve 49 against the valve seat 46 to closed position. An intake port 58 extends from the lower or outer face of the valve body 44 axially to each valve body 44 and offset from the valve seat 46 so as to communicate with the valve chamber 47 when the valve 49 is pulled away from the seat 46. The intake ports 58 are opened in accordance with the extent to which the valves 49 are pulled away from the valve seat 46. The outer end of each valve stem 51 is threaded and upon each threaded stem end 59 is an adjustable abutment nut 61.

The control of the valves in the valve body 44

is accomplished by a device that can be conveniently handled by squeezing on the handle 2. A hand lever 62 is pivoted on a pivot 63 near the upper end of the handle 2 and then extends downwardly. The free end of the hand lever 62 overlaps an arm 64 of a bell crank lever which is pivoted at an intermediate point thereof on a pivot 66 near the lower end of the handle 2. The lower arm 67 of the bell crank lever is widened into a double yoke as shown in Fig. 2 so that the openings 68 between the forks of the double yoke straddle the valve stems 51 and abut against the inside faces of the respective abutment nuts 61. Thus, when the hand lever 62 is pressed toward the handle 2 it moves the upper arm 64 of the bell crank toward said handle 2 and thereby forces the lower yoke arm 67 of said bell crank outwardly, which latter in turn engages the abutment nuts 61 and pushes the same outwardly so as to pull the valve stems 51 outwardly from the valve body 44 and thereby unseats the valves 49 from the valve seats 46 and opens communications through said valves. Suitable conduits 69, preferably of the flexible type, are connected to the intake ports 58 in the valve body 44 to conduct oxygen and gas to the respective intake ports 58.

The adjustment of the mixture is accomplished by adjusting the positions of the abutment nuts 61 on the respective valve stems 51. For instance, if equal amounts of gas and oxygen are required for the mixture, then the position is as shown in Fig. 3, namely the spacing of the abutment nuts 61 is the same from the valve seats 46 and both are simultaneously engaged by the yoke arm 67 of the bell crank. If less gas is needed for the mixture, then the abutment nut 61 on the valve stem 51 on the valve controlling the gas is unscrewed to space it away from the lower yoke arm 67 of said bell crank, thus the other valve controlling the air is first opened before the abutment nut 61 on the gas control valve is engaged and before the opening of the gas valve commences. Thus the opening of the gas valve will be relatively smaller than the opening of the air valve and a desired mixture is accomplished. In a similar manner a large variety of mixtures suitable for various conditions can be accomplished by merely adjusting the relative positions of the abutment nuts 61. The amount of mixture to be introduced is controlled by adjusting both nuts 61 to a greater or lesser distance from the valves 49 and accordingly to open the said valves to a lesser or greater extent by the movement of the lower end 67 of said bell crank, by selectively pressing the hand lever 62 for the desired feed.

In order to prevent the clogging of the nozzle by the dust particles, and to accomplish a uniform forced feeding of the same through said nozzle, I provide a dust flow control 6 at the intake end of the nozzle conduit 11. A valve body 71 is threaded upon the threaded end 21 of the nozzle conduit 11 so that the outlet port of said valve body 71 is communicated with the conduit 11 axially. A chamber 73 is formed in said valve body 71 so that it discharges substantially tangentially into said outlet or feeding port 72. Substantially at right angles to the axis of the feeding or outlet port 72 and on the other side of the chamber 73 is an intake port 74 also tangential to said chamber 73. The chamber 73 is substantially cylindrical and its axis is at right angles to the axis of the nozzle conduit 11 and offset to one side of the same. Through the axis

of the chamber 73 extends a shaft 76 from which latter extend radial blades 77. Each blade tapers axially outwardly so that its face rotating toward the intake port 74 is inclined at an angle with respect to the direction of the inflow between the blades, and the other face of the blade 77 is substantially at right angles to the axis. As the dust is forced under pressure through the intake port 74 it impinges upon the respective blades 76 and rotates them at a comparatively high rate of speed, and ejects the dust particles into the outlet port 71 and through the conduit 11. In this manner the flow is conducted in uniformly equal quantities as determined by the spacing between the blades 77 and by force of the pressure. This prevents the jamming or clogging at the feeding end or in the conduit 11.

The flow to the intake port 74 is controlled by a suitable valve, such as by a cock valve 78 which is rotatable in a transverse cylindrical valve seat 79 in the valve body 71 outside of the intake port 74. This valve is controlled by a suitable handle 81 for turning the cock valve 78 so that its valve passage 82 is aligned with the port 74 to a selected opening. The intake outside of said cock valve seat 79 is suitably provided with a flexible feed conduit 84 to conduct the dust under pressure to said valve body 71.

Thus in operation the operator first adjusts the nuts 61 to the required mixture, and then depresses the hand lever 62 toward the handle 2 and the oxygen flowing through the hole 32 draws in the required gas through the holes 31 and the mixture flows through the space between the stem 27 of the conduit 11 and the nozzle tip 24 and out through the passages around the knurled end 26 in jets surrounding that end of the conduit. The operator ignites this mixture and heats up the nozzle to the required temperature. The operator then adjusts the nozzle to the required angle with respect to the work and then, by turning the valve handle 81 of the cock valve 78, feeds the dust under pressure through the impeller heretofore described into and through the conduit 11, stem 27 and out at the knurled end where the dust particles are subjected to the surrounding flame and are properly conditioned to adhere to the surface of the work. The nozzle is also preheated by said flame so that the conduit itself is slightly heated and thereby the dust particles are suitably conditioned for action under the heat and for fusing upon the work with rapidity as required. The distribution of the dust and the flame all around results in a uniform fusing of the particles at the proper moment to achieve the proper coating of the work surface.

The agitator and pressure feed device 7 includes a housing 86 which is enclosed all around excepting at the end 87 thereof. On the bottom of this housing 86 is provided a jacket 88 which latter functions as a pressure chamber of compressed air. One end of this pressure chamber 88 is provided with an intake for a pressure line 89 through which compressed air is introduced into the chamber 88. The open end 87 of the casing 86 is covered by a cap 91 which is suitably secured in place on said end 87. Diametrically across the inside of said cap 91 is provided a distributing head 92 out of which extend a pair of spaced nozzles 93 and 94. The nozzle 93 extends at about axially with respect to the cap 91 on the casing 86 and is in the form of a conduit tapering toward its point. On the periphery, preferably on the surface or side of said tubular nozzle 93 are a plurality of staggered and spaced

nozzle orifices 96 through which the air under pressure is discharged in several forceful streams. The lower nozzle 94 is a comparatively wide and flat conduit which has on its upper face a plurality of elongated and staggered nozzle orifices 97 directed substantially toward the other nozzle 93. Both nozzles 93 and 94 communicate with the distributing head 92 so as to receive compressed air therefrom and discharge the air through said orifices 96 and 97 in staggered and overlapping streams of air creating a continuous whirl and agitation in the housing 86 and thereby maintaining the dust therein in a pulverized, loose mass and thoroughly intermixed with the air under pressure. Conduits 98 connect the outlet end of the jacket 88 to the distributing head 92 in the cap 91. A suitable valve 99 regulates the flow of the compressed medium through the conduits 98. While the dust may be fed automatically into the housing 86 for continuous operation in a larger unit, in the present illustration a light portable unit is shown wherein an inlet 101 is provided at about the middle of the top of the casing 86, which inlet is suitably covered by a removable plug 102 so as to permit the introducing of the dust into the housing 86 from time to time as required. Near the closed end of the housing 86 and at the top thereof is an outlet 103 to which is connected the flexible conduit 84 leading to the intake 83 of the valve body 71 on the spraying nozzle heretofore described.

The dust introduced through the intake 101 into the housing 86 is agitated and prevented from clogging or caking by the force of the compressed air jets issuing in overlapping staggered relation on parallel levels from the orifices 96 and 97 of the nozzles 93 and 94. The dust so intermixed with the air under pressure is forced through the conduit 84 to the valve body 71 wherein, controlled by the cock valve 78, it is passed by the impeller 76 to the feed conduit 11 and then through the stem 27 of said feed conduit out at the knurled end 26 of said nozzle conduit in the middle of the fusing flame jets surrounding said nozzle tip so as to be heated to a fusing point thereby and be sprayed upon the object to be coated.

A modified form of the nozzle tip structure is shown in Figs. 9 to 12 inclusive. In this form the discharge opening of the nozzle tip is shaped so as to flare or spread both the flames and the spraying of the dust. This tip may be made in suitable shapes for various types of spraying. In this form the discharge end of the nozzle tip 104 has on it a discharge end 106 formed in the shape of a flat funnel tapering outwardly and transversely of the nozzle tip 104 but having parallel flat sides 107. This results in a substantially oblong discharge opening 108. Into this funnel 106 fits a knurled discharge tip 109 conforming in the outer contour substantially to the tapering inner surface of the funnel 106. This discharge tip 109 is hollow and has a dust discharge slit 111, which, in the present illustration, has substantially cylindrical passages at its ends and in the middle with reduced straight slits connecting said passages. In the narrow end of the discharge tip 107 is threaded the forward end of a conduit stem 112 so as to conduct the dust into 70

5

said discharge tip 109. The inner end 113 of the conduit stem 112 is threaded into the end of the conduit 11. The passages between the knurls 114 on the discharge tip 109 determine the jets of flame in the oblong shape of the opening 108 so as to be in suitable proximity to the dust particles blown out through the discharge slit 111 of the tip 109. The resulting spray will be an outwardly flaring flat stream of heated particles to be fused upon the surface to be coated.

I claim:

1. In a spraying device of the character described, a nozzle body, means to discharge dust through said nozzle body, means to conduct a mixture of combustible medium through said nozzle body and around said dust discharge for heating the dust at approximately the point of discharge, a handle having a base, said base having passages therethrough, flexible conduits connected at one set of ends to the base in communication with the passages and at the other set of ends to the nozzle body and adapted to carry the components of the combustible medium to said nozzle body, adjustment means to connect said nozzle body to said handle and to hold said nozzle body at selected angular adjustment with respect to one another, and valve means for controlling flow of combustible medium through said passages.
2. In a spraying device of the character described, a nozzle body, means to discharge dust through said nozzle body, means to conduct a mixture of combustible medium through said nozzle body and around said dust discharge for heating the dust at approximately the point of discharge, a handle having a base, said base having passages therethrough, flexible conduits connected at one set of ends to the base in communication with the passages and at the other set of ends to the nozzle body and adapted to carry the components of the combustible medium to said nozzle body, adjustment means to connect said nozzle body to said handle and to hold said nozzle body at selected angular adjustment with respect to one another, means at the other set of ends of the passages to connect supply conduits to said handle, and valve means for controlling the flow of combustible medium through said passages.

MANUEL A. SANDORA.
